UNITED STATES PATENT OFFICE.

HERBERT A. WARREN, OF WOBURN, MASSACHUSETTS.

TRUSS PAD.

1,422,153.

Specification of Letters Patent. Patented July 11, 1922.

Application filed August 17, 1921. Serial No. 492,899.

To all whom it may concern:

Be it known that I, HERBERT A. WARREN, a citizen of the United States, residing at Woburn, in the county of Middlesex and 5 State of Massachusetts, have invented new and useful Improvements in Truss Pads, of which the following is a specification.

This invention relates to hernial trusses, and has for its object to provide an improved 10 pad, including a body portion adapted to be supported by a belt, and a pressure applicator supported by the body portion and adapted to bear on an affected part, and to have a limited universal tipping movement 15 relatively to the body portion, so that the applicator may apply the desired pressure without being displaced from its operative position by movements of the belt.

The invention is embodied in the improvements which I will now proceed to describe 20 and claim.

Of the accompanying drawings forming a part of this specification,—

Figure 1 is a side view of a pad embodying the invention, looking toward the inner side.

Figure 2 is a section on line 2—2 of Figure 1.

Figure 3 is a side view looking toward the 30 outer side, or back of the pad.

Figure 4 is a perspective view, showing two pads engaged with a belt.

Figure 5 is a view similar to Figure 2, showing a modification.

Figure 6 is a side view of the spring shown by Figure 5.

In the drawings, 12 represents an annular body having a base adapted to bear on a supporting member, and a central socket 40 13, extending inwardly from the outer side of the body and of greater diameter at its outer than at its inner end, as shown by Figure 2, the socket having a reduced open inner end within the body, and spaced from 45 the base thereof. Loosely engaged with the body 12 to have a limited universal movement relatively thereto, is a pressure applicator composed of a shank 14, extending through the socket 13, and an enlarged 50 head 15 projecting outward from the body, and of greater diameter than the socket. The shank is provided with an enlargement 16, bearing loosely on the inner end of the socket 13. The body is provided with a 55 spring engaged with and extending across the base portion of the body and bearing on

the inner end of the shank, to exert an outward yielding pressure on the applicator, outward movement of the applicator by the spring being limited by the enlargement 16. 60

The body is provided with means whereby it may be secured to a belt 17, adapted to encircle the body of the wearer. In the preferred embodiment of the invention, shown by Figures 1, 2, 3 and 4, the belt-engaging means and the spring are parts of an elastic strap 18, preferably of ordinary elastic webbing, said strap having a looped portion engaged with marginal portions of the body 12. Said looped portion includes 70 an outer stretch 18^a extending across the back of the body, and an inner stretch 18^b, extending across the open end of the socket 13. The strap is passed through slots 19, 19, at diametrically opposite portions of the body 12, and one of its ends is attached at 20 to the main portion of the strap. 75

The strap is under tension when secured as described, so that its inner stretch 18^b constitutes a spring exerting an outward yielding pressure on the applicator. The elasticity of the outer stretch 18^a enables it to be displaced to permit the insertion of the belt 17 between the back side of the 80 body 12 and the said outer stretch, as indicated by Figure 4. The shank enlargement 16 is adapted to tip freely in various directions in the space between the inner end of the socket and the base of the body, 85 while in contact with the inner end of the socket. The form of the shank and of the socket is such that the shank is adapted to have a limited tipping movement in any direction in the socket, as 90 indicated by Figure 2, one extreme of the tipping movement being indicated by dotted lines. The applicator is capable of a limited longitudinal movement in the socket, so that it may be forced slightly 95 100 inward against the pressure of the spring, and normally held at the extreme of its outward movement by the spring. The applicator is therefore capable of a limited universal tipping movement, on a fulcrum 105 formed by the inner end of the socket, so that the head 15 is adapted to bear on an affected part without being caused to slip thereon by movements of the belt and of the body 12 relatively to said part. The 110 enlarged head 15 is held by the spring offset from the outer side of the body, and a por-

tion of the head bears on the outer side of the body when the applicator is tipped, said bearing limiting the tipping movement.

The strap 18 is elongated and provided 5 with means whereby it may be additionally engaged with the belt 17. As shown by Figure 4, the strap is bifurcated, and provided with end portions 18^a, adapted to be bent over the upper edge of the belt 17, 10 and detachably secured thereto by separable snap fasteners, one member of one of the fasteners being shown at 22.

Figure 5 shows a modified construction, which includes a spring 23, which is independent 15 of the means for engaging the body 12 with the belt. Said spring may be of resilient sheet metal, and of spider form, as shown by Figure 6, the outer ends of the arms of the spring bearing on a flange 12^a formed on the back side of the body 12.

Any suitable independent means may be employed for engaging the body 12 with the belt 17, such as a metal strap 24, attached at its ends at 25 to the body, and spaced 25 from the back side of the body to permit the insertion of the belt between it and the body.

The body 12 is preferably made of semi-hard rubber, having sufficient elasticity or 30 compressibility to permit the engagement of the applicator with the body by forcibly pressing the shank 14 into the socket 13, the contracted portion of the socket being slightly expanded and permitting the enlargement 35 16 to pass through it, the socket then contracting to prevent the withdrawal of the enlargement. The applicator may be made of the same or a different material.

I claim:

40 1. A truss pad comprising an annular body having a base portion, formed to bear on a supporting member, a socket extending inwardly from the outer side of the body,

and of greater diameter at its outer than at its inner end, the latter being open; 45 a pressure applicator including a shank extending entirely through the socket, and having an enlargement at its inner end, and an enlarged head of greater diameter than the socket; and a spring which normally holds the shank enlargement against the inner end of the socket, and the head offset from the outer side of the body, the shank and socket being formed to permit a universal tipping movement of the 55 applicator relatively to the body, on a fulcrum formed by the inner end of the socket, said movement being limited by the bearing of a portion of the enlarged head against the outer side of the body. 60

2. A truss pad comprising a body having a central socket which is open at the back side of the body, an elastic strap having a looped portion engaged with marginal portions of the body, said looped 65 portion extending across the back of the body and adapted to be engaged with a belt, and an inner stretch extending across the open end of the socket, and constituting a spring, and a pressure applicator composed of a shank extending through the socket and bearing on said spring, and a head projecting outward from the body, the shank being provided with an enlargement limiting its outward movement by 70 the spring, the applicator being adapted to have a limited universal movement in the socket. 75

3. A truss pad substantially as specified by claim 2, said strap being elongated and 80 extended from the body and provided with means whereby it may be additionally engaged with a belt.

In testimony whereof I have affixed my signature.

HERBERT A. WARREN.
